Primary Examiner — Wendy L Arminio*Assistant Examiner* — Sherry L Jones*(74) Attorney, Agent, or Firm* — Falcon Rappaport & Berkman LLP(57) **CLAIM**

The ornamental design for a pet cage, as shown and described.

DESCRIPTION

FIG. 1 is a top, front, left side perspective view of a pet cage according to the present disclosure;

FIG. 2 is a bottom, front, right side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The shade lines shown in the drawings indicate the character and contour of surfaces represented and should not be confused with surface ornamentation.
